UNITED STATES PATENT OFFICE

2,099,245

MOTION PICTURE FILM TREATING
APPARATUS

Frederick B. Thompson, Hollywood, Calif.

Application July 21, 1936, Serial No. 91,710

16 Claims. (Cl. 271—2,3)

This invention has to do in a general way with continuous processes for treating motion picture film and is more particularly related to improvements in film supporting and moving means for conducting the film through an apparatus in which such a process is carried out. More specifically, my invention is directed to improvements in the film supporting and carrying apparatus of the general type shown and described in United States Letters Patent No. 1,933,127 entitled "Method and apparatus for developing and drying motion picture film" which was issued to me on October 31, 1933.

In the apparatus shown in my prior patent above referred to, I employ a series of parallel film supporting rollers over which the film hangs in loops which extend downwardly from opposite sides of the rollers, such loops passing under and over sets of intermediate rollers so that it travels in opposite directions over the successive film supporting rollers of the series. These film supporting rollers are associated with driven rollers arranged so that the alternate rollers of the series are driven in the same direction, the successive rollers rotating in opposite directions.

The entire system of rollers in one treating tank of the apparatus shown in my prior patent was supported on a single shaft and means were provided for lifting the shaft away from the driving rollers to arrest their operation in the event a film should break or the operator for any other reason should desire to stop the operation.

It is a primary object of this invention to provide an apparatus of the general character described in which the successive rollers instead of being mounted on a common shaft, are individually supported. It is one important feature attending this construction that such rollers may be individually removed for inspection and repair or replacement without necessitating a complete dismantling of the machine.

It is another important feature of this invention that the individual rollers are associated with yieldable counter-balance means in the form of a weight or a spring such means being constructed so that the drag or tension on a film passing over the roller is effective to hold the film supporting roller in engagement with its corresponding driving roller and in the event such tension or drag is relieved by the breakage of film or otherwise, the film supporting roller is automatically lifted by the counter-balancing means away from its driving roller so that its operation is immediately arrested. This prevents the accumulation of film within the tank or dry-

ing chamber which would be occasioned if the rollers were permitted to operate over any period of time after the film had broken. This construction, therefore, eliminates the necessity of an operator constantly watching the machine and being ready to manually stop the drive or raise the roller unit from contact with the driving rollers in the event film breakage should occur.

It is a still further object of this invention to provide a novel design and construction in a roller and counter-weight mechanism which affords an extremely compact unit and in which the counter-weights are protected from engagement with passing objects by the film carrying flange on the film supporting rollers associated therewith.

The details in the construction of a preferred form of my invention, together with other objects attending its production will be best understood from the following description of the accompanying drawings which are chosen for illustrative purposes only and in which—

Fig. 1 is a sectional elevation through a tank or chamber equipped with one preferred form of film carrying means contemplated by this invention;

Fig. 2 is a sectional elevation taken in a plane represented by the line 2—2 of Fig. 1;

Fig. 3 is an enlarged fragmentary sectional elevation with parts broken away illustrating further details in the construction of a preferred form of film supporting roller and counter-weight mechanism;

Fig. 4 is a sectional elevation taken in a plane represented by the line 4—4 of Fig. 3;

Fig. 5 is a plan section along the line 5—5 of Fig. 3; and

Fig. 6 is a sectional elevation showing a modified construction of the roller and counter-balancing means.

More particularly describing the invention as herein illustrated, reference numeral 11 indicates a chamber which may be either a developing, washing or fixing tank, or a drying chamber. This chamber contains what I may term a frame member generally indicated by reference numeral 12, such member comprising end plates 13 which are supported in the chamber by bracket pieces 14 and 14', the end plates carrying standards 15, the lower ends of which in turn support cross members 16. A longitudinal beam or frame member 17 is carried at its ends between two oppositely disposed end plates 13.

The beam member 17 is provided with a plurality of longitudinally spaced sockets 19 which

are adapted to receive pins 20 mounted on the lower ends of roller supporting standards 21. Each of the standards 21 carries what I may term a film supporting roller, such rollers being generally indicated by reference numerals 22 and 22'.

Extending longitudinally across the frame immediately below the rollers 22—22', etc., I provide a pair of shafts 24 and 25. These shafts 10 in this embodiment of my invention are shown as being supported by bearings 26 in the end plates and the shaft 25 is equipped with a miter gear 27 keyed thereto, such gear being in mesh with another gear 28 which is mounted on the 15 lower end of an auxiliary drive shaft 29. The drive shaft 29 is carried by bearings 30 and 31 which are mounted on the end plate and the upper end of the drive shaft is equipped with a miter gear 33 which is driven through the 20 medium of a gear 34 from a main drive shaft 35 extending throughout the length of the unit.

In this latter connection, it will be understood that a plurality of tanks or chambers equipped with film carrying devices of the character shown 25 herein will generally be employed in a series to constitute a continuous film treating unit and the individual banks of rollers with their associated mechanism will all be driven from the shaft 35 which in turn is operated from a suitable 30 source of power not shown.

The shafts 24 and 25 are provided with meshing spur gears 24g and 25g so that they are driven in opposite directions. The shaft 25 is equipped with a plurality of driving rollers 40 and 40' 35 which are keyed thereto and are positioned so as to be engaged by alternate film supporting rollers 22. Keyed to the shaft 24 beneath the film supporting rollers 22' which are between the film supporting rollers 22, I provide additional 40 driving rollers 41 which rotate the roller 22' in a direction opposite to that of the rollers 22. It should be pointed out at this time that my invention also contemplates a device in which the alternate rollers only of the series are driven, in 45 which event the rollers 22' between the driven rollers 22 would merely act as guide supports for the film and receive their rotation from the film itself.

Reference numerals 47 and 47' indicate guide 50 rollers which are mounted on brackets 48 and 48' secured to the upper edge of the brackets or angle members 14. Reference numerals 49 and 50 indicate loop maintaining rollers which are mounted on shafts 51 and 52, such shafts being 55 carried by bearings in the cross members 16. Reference numerals 53 and 54 indicate loop return rollers which are carried on stub shafts 55 and 56 mounted on opposite faces of the longitudinal beam member 17.

60 In the use of this film driving unit, like that shown and described in my prior patent referred to above, a motion picture film passes over the roller 47 and downwardly beneath the first loop maintaining roller 49. It then passes upwardly 65 in a loop over the first loop return roller 54 and downwardly over the next loop maintaining roller 49' which is carried by the shaft 51. In this connection it will be observed from Figs. 1 and 2 that the film is turned through 90° as it passes from the roller 49 over the roller 54 and is turned back 70 again through 90° as it travels down from the roller 54 to the roller 49'.

The roller 49' is in direct alignment with the 75 first film supporting roller 22 which is being driven in the direction of the arrow shown in

Fig. 1 by its driving roller 40. The film passes upwardly from the roller 49' over the roller 22 and through its frictional engagement with this last mentioned roller is advanced through that part of the roller system. As the film leaves the 5 roller 22, it is conducted downwardly beneath the first roller 50 on the shaft 52 (see Fig. 2) which is opposite the roller 49' on the shaft 51. After passing downwardly beneath the first roller 50, the film passes upwardly over the first loop return roller 53 and down below the next loop maintaining roller on the shaft 52 which is opposite the roller 49a of shaft 51. The roller 49a and the loop maintaining roller on the shaft 52 last referred to (as will be observed from Fig. 1) 15 are in line with the second film supporting roller 22' of the series and the film leaving the second loop maintaining roller on the shaft 52 passes upwardly and over the film supporting rollers 22' over which it is driven in the direction of the 20 arrow on that roller in Fig. 1. From this arrangement it will be seen (Fig. 2) that the film hangs in independent loops on opposite sides of the successive rollers in the series and that film travels in opposite directions over the successive 25 rollers and in the same direction over alternate rollers. This construction and operation is fully described in my prior patent referred to above.

As has been previously pointed out, it is one 30 object of this invention to provide a film carrying unit of the class described in which the film supporting rollers are independently mounted and can be readily removed for inspection or replacement. This is accomplished by mounting the rollers 22 and 22' on individual standards 21, 35 such standards being carried in the sockets 20. In order to hold the rollers in proper alignment and to prevent the rotation of their supports when they are installed, I consider it preferable to notch the beam member 17 as indicated at 50, 40 such notches receiving the lower ends of the standards 21 as is best illustrated in Fig. 3.

It was also pointed out as an object of this 45 invention to provide means for automatically lifting the film supporting rollers away from their respective drive rollers in the event the tension or drag on the film loop carried by any one of these rollers was relieved by breakage of the film or otherwise. In the preferred embodiment of 50 my invention, shown in Figs. 1 to 5 inclusive, this is accomplished by counter-balancing the individual rollers. The details of this counter-balanced construction are best illustrated in Figs. 3 to 5 inclusive and will now be described.

It will be observed that the standard 21 in the 55 region of the center of the roller 22 is provided with an offset portion 63. This offset portion has a pivot pin 61 secured therein, such pivot pin carrying a lever member 62 which is held against longitudinal movement on the pivot pin by means of a screw or pin 63, the inner end of which extends into an annular groove 64 formed on the pin. The inner end of this lever member 62 receives a screw member 65, the threaded end of 60 which extends upwardly from the lever into an opening or slot 66 formed in the standard 21 and constitutes a stop for limiting the swinging movement of the lever. The portion 67 of the screw adjacent the head 68 thereof is enlarged and 65 comprises a bearing for the hub portion 69 of the film supporting roller 22. In this form of my invention the roller is shown as having a solid web 70 70, the periphery of which is equipped with a film supporting flange 71 which is offset to encompass 75

the lever member and is provided with radially extending guide flanges 72 and 72'.

It will thus be seen that the roller 22 is swingably supported on the standard through the medium of the lever member 62 and the positions of the pivotal support for the lever and the lower edge of the opening 66, which constitutes the stop for downward movement of the lever are such as to permit the roller being drawn downwardly into engagement with the driven roller 40 by the tension or drag of a film F passing over the film supporting roller 22.

In order that the film supporting roller may be automatically and immediately swung upwardly away from its corresponding driven roller when the drag or tension on the film F is relieved, I provide the end of the lever member 62 opposite the end which carries the roller 22 with counter-balancing means such as a counter-weight 73, the mass of which is sufficient to lift the roller 22 in the manner described above when such roller is relieved of the drag or tension from the film. The counter-weight 73 is shown as being notched as indicated at 74 to fit over the end of the lever 62 and is secured thereto through the medium of a screw 75. In this form of my invention the counter-weight 73 serves the additional function of locking the pin 63 in place since it is made of a width such that it extends over the outer end of the pin or screw member 63.

In the form of my invention shown in Fig. 6, I show a modified construction for obtaining the counter-balanced action in the film supporting roller 22b. This roller is rotatably mounted directly on a standard 21b through the medium of a bearing pin indicated at 80. The lower end of the standard 21b is provided with a supporting pin 20b which is received in a socket 81 formed in the beam member 17b of the frame which corresponds to the beam member 17 shown in Figs. 1 to 5 inclusive.

In this form of my invention the socket 81 is made of sufficient depth to contain a compression spring 82 in the bottom thereof, the upper end of such spring bearing against the bottom of the pin 20b. The roller 22b is normally held in engagement with its corresponding driving roller 40b by the tension on the film F' and in the event this tension is relieved in any manner, such as by breakage in the film, the compression spring 82 is effective to lift the pin 20b and the roller unit carried thereby so that the roller 22b is disengaged from the roller 40b.

It will be understood that other types of construction may be employed in obtaining a counter-balanced roller of the class described above, also that such a film supporting and driving roller may be employed in conjunction with other arrangements of film carrying roller systems.

The arrangement described and illustrated herein, however, has certain inherent advantages in that it may be economically manufactured and easily assembled, it has a minimum number of parts and by forming the film supporting roller and the counter-balance lever so that the flange of the roller encompasses the counter-balance, I have provided convenient means for protecting the counter-balance and the lever against inadvertent movement through engagement with outside objects.

It is to be understood that while I have herein described and illustrated one preferred form of my invention, that the invention is not limited to the precise construction or arrangement described above, but includes within its scope what-

ever changes fairly come within the spirit of the appended claims.

I claim as my invention:

1. In a film treating apparatus, the combination of: a frame; a supporting member in said frame; a plurality of standards individually removably mounted in said supporting member; and a film supporting roller rotatably carried by each of said standards. 5

2. In a film treating apparatus, the combination of: a frame; a supporting member in said frame; a plurality of standards individually removably mounted in said supporting member; a film supporting roller rotatably carried by each of said standards and roller driving means in said frame beneath some of said film supporting rollers adapted to be engaged by the corresponding film supporting rollers for imparting rotation thereto. 10

3. In a film treating apparatus, the combination of: a frame; a supporting member in said frame; a plurality of standards removably mounted in said supporting member; a film supporting roller rotatably carried by each of said standards; driving rollers in said frame beneath some of said film supporting rollers, said supporting rollers being normally held in engagement with the corresponding driving rollers by the tension of a film passing thereover; and counter-balance means associated with said supporting rollers for automatically lifting same out of engagement with the corresponding driving roller when said film tension is relieved. 20

4. In a film treating apparatus, the combination of: a frame; a plurality of film supporting rollers; means supporting said rollers in said frame for vertical shifting movement; driving rollers in said frame beneath some of said film supporting rollers for rotating the film supporting rollers; said film supporting rollers being normally held in engagement with the corresponding driving roller by the tension of a film passing thereover; and means associated with said film supporting rollers and said roller supporting means for automatically lifting same out of engagement with the corresponding driving rollers when the film tension is relieved. 35

5. For use in a film treating apparatus, a film supporting and driving unit embodying: a frame member; a standard mounted on said frame member; a lever member pivotally mounted on said standard; a film supporting roller rotatably mounted on one end portion of said lever member; a flange on the periphery of said roller adapted to support a film; a driving roller positioned beneath said film supporting roller and adapted to be engaged thereby under the action of a film carried by the latter roller; and a counterweight on the other end of said lever member for automatically lifting said film supporting roller away from said driving roller when the film tension is relieved. 45

6. For use in a film treating apparatus a film supporting and driving unit embodying: a frame member having a socket therein; a standard having a lower end portion removably received in said socket; a lever member pivotally mounted on said standard; a film supporting roller rotatably mounted on one end portion of said lever member; a flange on the periphery of said roller adapted to support a film; a driving roller positioned beneath said film supporting roller and adapted to be engaged thereby under the action of a film carried by the latter roller; and a counterweight on the other end of said lever member 55

70

75

for automatically lifting said film supporting roller away from said driving roller when the film tension is relieved.

7. For use in a film treating apparatus a film supporting and driving unit embodying: a frame member having a socket therein; a standard having a lower end portion removably received in said socket; means for holding said standard against rotation in said socket; a lever member pivotally mounted on said standard; a film supporting roller rotatably mounted on one end portion of said lever member; a flange on the periphery of said roller adapted to support a film; a driving roller positioned beneath said film supporting roller and adapted to be engaged thereby under the action of a film carried by the latter roller; and a counterweight on the other end of said lever member for automatically lifting said film supporting roller away from said driving roller when the film tension is relieved.

8. For use in a film treating apparatus a film supporting and driving unit embodying: a frame member; a standard mounted on said frame member; a lever member pivotally mounted on said standard; a film supporting roller rotatably mounted on one end portion of said lever member; a flange on the periphery of said roller adapted to support a film; a driving roller positioned beneath said film supporting roller and adapted to be engaged thereby under the action of a film carried by the latter roller; a counterweight on the other end of said lever member for automatically lifting said film supporting roller away from said driving roller when the film tension is relieved and stop means associated with said lever and said standard for limiting the swing movement of said lever.

9. For use in a film treating apparatus a film supporting and driving unit embodying: a frame member; a standard mounted on said frame member; a lever member pivotally mounted on said standard; a film supporting roller rotatably mounted on one end portion of said lever member; a flange on the periphery of said roller adapted to support a film; a driving roller positioned beneath said film supporting roller and adapted to be engaged thereby under the action of a film carried by the latter roller; a counterweight on the other end of said lever member for automatically lifting said film supporting roller away from said driving roller when the film tension is relieved, the length and width of said lever and counterweight assembly being such that it is encompassed by the flange of said film supporting roller.

10. For use in a film treating apparatus a film supporting and driving unit embodying: a frame member; a standard mounted on said frame member; a lever member pivotally mounted on said standard; a bearing pin mounted in one end of said lever member; a roller member having its hub journaled on said bearing pin; a peripheral flange on said roller adapted to support a film, said flange being formed so as to encompass said lever member; a driving roller beneath said film supporting roller adapted to be engaged thereby under the action of a film on said supporting roller; and a counterweight on the other end of said

lever for lifting said film supporting roller away from said driving roller when the tension on said film is relieved.

11. In a film treating apparatus, the combination of: a frame; a plurality of film supporting rollers; means supporting said rollers in said frame for vertical shifting movement; driving rollers in said frame beneath some of said film supporting rollers for rotating the film supporting rollers; said film supporting rollers being normally held in engagement with the corresponding driving roller by the tension of a film passing thereover; and counterweight means associated with said film supporting rollers and said roller supporting means for automatically lifting same out of engagement with the corresponding driving rollers when the film tension is relieved.

12. In a film treating apparatus, the combination of: a frame; a plurality of film supporting rollers; means supporting said rollers in said frame for vertical shifting movement; driving rollers in said frame beneath some of said film supporting rollers for rotating the film supporting rollers; said film supporting rollers being normally held in engagement with the corresponding driving roller by the tension of a film passing thereover; and yieldable means associated with said film supporting rollers and said roller supporting means for automatically lifting same out of engagement with the corresponding driving rollers when the film tension is relieved.

13. In a film treating apparatus, the combination of: a frame; a plurality of film supporting rollers; means supporting said rollers in said frame for vertical shifting movement; driving rollers in said frame beneath some of said film supporting rollers for rotating the film supporting rollers; said film supporting rollers being normally held in engagement with the corresponding driving roller by the tension of a film passing thereover; and spring means associated with said film supporting roller and said roller supporting means for automatically lifting same out of engagement with the corresponding driving rollers when the film tension is relieved.

14. In a film treating apparatus the combination of: a frame; a supporting member in said frame; a supporting standard removably mounted in said supporting member; a film supporting roller rotatably carried by said standard; and a compression spring interposed between said standard and said supporting member for lifting said standard away from said supporting member.

15. In a film treating apparatus the combination of: a frame; a plurality of standards individually removably and resiliently mounted in said supporting member; and a film supporting roller carried by each of said standards.

16. In a film treating apparatus, the combination of: a frame; a supporting member in said frame; a plurality of standards individually removably mounted in said supporting member; a film supporting roller carried by each of said standards; and a compression spring interposed between each of said standards and said supporting member.

FREDERICK B. THOMPSON.
